UNITED STATES PATENT OFFICE.

ANSON C. MILLS, OF JACKSON, MICHIGAN, ASSIGNOR TO JACKSON FENCE COMPANY, OF JACKSON, MICHIGAN, A CORPORATION OF MICHIGAN.

TENSIONING DEVICE FOR WIRE-FABRIC MACHINES.

1,282,909.

Specification of Letters Patent. Patented Oct. 29, 1918.

Application filed January 11, 1917. Serial No. 141,902.

To all whom it may concern:

Be it known that I, ANSON C. MILLS, a citizen of the United States, and resident of Jackson, in the county of Jackson and State 5 of Michigan, have invented certain new and useful Improvements in Tensioning Devices for Wire-Fabric Machines, of which the following is a specification.

My invention relates to the wire industry, 10 and has particular reference to a novel tensioning device for use in connection with wire fabric machines.

In many branches of the wire industry, and particularly in the formation of wire 15 fabric for fences, concrete reinforcement, etc., it is necessary to employ a tensioning device, to the end that the tension of all the wires in the fabric shall be the same. This has heretofore been accomplished by the use 20 of separate wheels around which the various line wires were led, the wires being usually given a single turn around the wheels, and being held against slipping by means of spring clamps adjusted to grasp the wire as 25 it entered upon the wheel, cams being used to positively retract the clamps and release the wire at the proper point. This mechanism has heretofore been somewhat complicated in construction and it is to the im- 30 provement thereof that the present invention relates. In the device shown in the drawings the clamping mechanism is of very simple form, all of the line or strand wires being held on the drum by a single clamping 35 mechanism which is actuated by a simple cam and lever. Three series of such clamping devices are provided on the periphery of the drum and all of the clamps of a single series are actuatable in unison by a single 40 mechanism.

The invention will be more readily understood by reference to the accompanying drawings, wherein—

Figure 1 is a vertical section through a 45 tensioning device such as is contemplated by me;

Fig. 2 is an end elevation of the drum partly in section, the view being taken on the line 2—2 of Fig. 1;

Fig. 3 is an end elevation of the drum 50 showing the means for operating the clamp controlling cam;

Fig. 4 is a fragmentary detail showing the means which I prefer to employ for compensating for the omission of one or more wires 55 in the series, and

Fig. 5 is a plan view of the construction shown in Fig. 4.

Referring more particularly to the drawings, it will be seen that on a shaft 10, 60 mounted in suitable bearings, are keyed the spiders 11, 12. To the spiders is secured a cylinder 13 having longitudinal grooves 14 in its periphery, three of such grooves being shown in spaced relation on the cylinder. 65 Within the deeper portion of the groove is mounted the base of the wire clamps or jaws 15. These clamping members are provided with flanges 16 at their base portion, strips or caps 17, which are mounted in the shal- 70 lower portion of the groove 14 overlying the flanges 16 and preventing the removal of the clamp. The arrangement is such that the clamps or jaws are freely slidable longitudinally in the grooves in the cylinder and provision is made for sufficient of these clamps to accommodate the required number of line wires in the fabric to be woven, the wires being accommodated between adjacent clamps, as best shown in Fig. 1. 75

As an end stop I prefer to provide an arm 18 on the cylinder, this arm projecting upwardly into the plane of the jaws or clamps. Mounted within a threaded opening in the arm is a cap bolt 19 held in adjusted position 80 by a lock nut 20, the head of the cap bolt contacting the extreme clamp in the series. The means for clamping the members 15, as best shown in Fig. 1, consist of an arm or lever 21, pivoted at 22 to a portion 23 of the 85 cylinder, the short arm 24 of the member 21 contacting the adjacent clamping member. On the longer arm of the part 21 is mounted a frusto conical roller 25, which roller cooperates with a disk 26 having a face 27 90 beveled to correspond to the roller 25. An interruption 28 in the surface 27 of the disk provides for releasing the clamping pressure inserted by the arm 21 on the wire-holding 95 jaws, the disk remaining in stationary position, except as hereinafter noted. The disk is mounted on a sleeve 29, and to a reduced portion 30 of the sleeve is secured a hand wheel 31 which is provided near its outer diameter with a pin 32. This pin co-operates 100 with a notch in a latch 33 pivoted at 34 to a portion of the frame of the machine. It is always desirable in the case of breakage of a strand wire to release such wire from the tensioning device in order to secure sufficient slack for splicing. This is accomplished by stopping the rotation of the cyl- 105

inder and of the fabric machine, releasing the hand wheel, then rotating the same together with the cam disk, thereby bringing the reduced portion 28 of the disk into co-operation with the respective rollers 25 which control the clamping devices and successively removing the broken wire from engagement with the clamp.

At times a fabric is constructed which 10 does not require the use of the maximum number of strand wires provided for in a tensioning device. In that case I provide a filler, such as is shown in Figs. 4 and 5, which may consist in a piece of metal 35, 15 bent into angular form, one of the legs of the angle being of a thickness corresponding substantially to that of the wires employed. The other leg of the angle may be secured by a screw 36 to one of the clamping members. An advantage in the use of 20 a device such as disclosed is in its simplicity and small initial cost. Furthermore, the cost of maintenance is slight, due to the fact that the number of parts is reduced 25 to a minimum and the moving parts are readily removed and replaced with small cost. While I have described but one of the series of clamping devices which I provide on the periphery of the drum, it will 30 be understood that the others are duplicated and may be increased or diminished in number as desired. Furthermore, it is obvious that modifications may be made in the construction shown without departure 35 from the spirit of my invention.

I claim:

1. In a device of the class described, the 40 combination of a drum, a plurality of independent, longitudinally slideable blocks carried by said drum and between which blocks the wires to be tensioned are adapted to be held, a lever bodily movable with said drum and pivoted thereon, one arm of said lever contacting an extreme block, the other end 45 of said lever carrying an anti-friction roll, a normally stationary cam with which said friction element co-operates, and manually operable means for rotating said cam as required to release said blocks, substantially 50 as described.

2. In a device of the class described, the 55 combination of a drum having a plurality of grooves in its periphery, said grooves extending longitudinally of the drum, and a plurality of independent longitudinally slideable blocks mounted in said groove and arranged to provide a space therebetween for the accommodation of wires, a rigid stop at one end of said drum against which said 60 blocks may abut, a lever pivoted intermediate its end to said drum, one end of said lever acting upon an extreme block, an anti-

friction element mounted on the other end of said lever, a face cam normally non-rotatable with relation to said drum, said cam being interrupted at one point, thereby permitting the release of the wires held between said block and the entrance of wires at another point in the rotation of said drum, and manually operable means for rotating said cam independent of said drum, whereby said wires may be released at points other than the point at which the wires are normally released in the operation of the drum, substantially as described.

3. In a device of the class described, the combination of a drum having a plurality of longitudinal grooves in its periphery, a plurality of independent, longitudinally slideable blocks mounted in said groove, 80 levers mounted on said drum and contacting the end block in each series, a single cam for actuating all of said levers, said cam having an interruption whereby said blocks are sequentially released from clamping engagement with said wires, means for shifting said cam independently of the rotation of the drum, whereby said block may be released and a wire removed from engagement therewith during the idleness of the drum, 90 substantially as described.

4. In a device of the class described, the combination of a drum having a plurality of longitudinal grooves in the surface thereof, a plurality of independent longitudinally slideable blocks mounted in said grooves and providing a space between adjacent blocks for the accommodation of wires, automatic means for clamping and unclamping said block to release and clamp said wires; and 100 means for filling the space between adjacent blocks when a wire is not applied thereto, substantially as described.

5. In a device of the class described, the combination of a drum having a plurality of longitudinal grooves in the surface thereof, a plurality of independent longitudinally slideable blocks mounted in said grooves and providing a space between adjacent blocks for the accommodation of wires, automatic 110 means for clamping and unclamping said block to release and clamp said wires, said clamping means being constructed to rigidly hold the wires without spring resistance, and means for filling the space between adjacent blocks when a wire is not applied thereto, substantially as described.

Signed at Chicago, Illinois, this 12th day of December, A. D. 1916.

ANSON C. MILLS.
